UNITED STATES PATENT OFFICE

2,586,115

BUSHING TYPE ELECTRIC CIRCUIT BREAKER

Otoyuki Tange and Seiiti Morita, Taga-Mati,
Taga-Gun, Japan, assignors to Hitachi Limited,
Tokyo, Japan, a corporation of Japan

Application May 25, 1949, Serial No. 95,294

3 Claims. (Cl. 200—150)

1

This invention relates to electric circuit breakers, and more particularly to an electric circuit breaker immersed in an oil filled bushing, and has for its object to provide an electric circuit breaker having higher insulating strength between two electrodes in case of opening circuit.

A further object is to stabilize the circuit interrupting effect after the electric arc had been extinguished.

Another object of the invention is to prevent the creeping discharge or flash over between electrodes along the inner surface of insulating cylinder enclosing arc suppressing chamber therein owing to the deposition of carbonaceous substances or to the deterioration of dielectric strength of insulating oil by the invasion of moistures, which is liable to occur in an ordinary circuit breaker of this kind having a series of arc suppressing chambers arranged in an insulator cylinder extending between two fixed electrodes in case of opening the contact.

With the above objects in view the invention consists of novel details of construction and combination of parts hereinafter fully described and claimed.

Referring now to the drawing:

A single figure is a sectional elevation of a bushing type oil circuit breaker embodying this invention.

Referring now to the drawing, 10 designates an insulator cylinder, such as a porcelain bushing, which is oil-tightly sealed at its bottom by a metal cover 11 and secured to a metal cap 12 put on supporting insulator 13. 14 designates an upper metal casing which is secured tightly to the top of the bushing 10 and encloses therein a suitable switch operating mechanism 15. 16 designates an operating insulator for the mechanism 15.

According to the present invention, a protective insulator cylinder 17 is suspended from the upper casing 14 by means of metal pieces 18 and a cylinder 19 of insulating material such as Bakelite cylinder is put in the cylinder 17 and secured to its bottom 20. A number of arc suppressing chambers 21 are formed in the cylinder 19 and a lower stationary electrode 22 is fixed in the cylinder 19. 23 is a conductor rod fitting into the lower contact piece 24 fixed to the bottom plate 11 and engaging in a hole 25. 26 is a terminal lead, 27 an upper stationary electrode fixed to the pillar 28. 29 designates a moving electrode passing through the member 27 and guided thereby, 30 is an upper ter-

2

minal lead. It is an essential feature of the invention that the insulating oil gap G is provided between the top of the arc suppressing cylinder 19 and the lower end of the cylinder 21 enclosing the upper fixed electrode 27 and forming the circuit interrupting chamber 32 therein. 33 represents insulating oil.

The above construction is most effective in positively increasing the insulating strength between the fixed electrode 22 and the lower end of the moving electrode 29 in its circuit open position and in absolutely preventing the re-arching phenomena since gases generated and following the moving electrode 29 when the electrode is moved upwards aparting from the lower electrode 22 can freely expand and find the way through the oil gap G into the annular oil space between the cylinders 17 and 19, and finally the lower end of the electrode 29 passes through the oil gap G and retires into the chamber 32 so that the electrode 29 can easily get rid of gaseous zone. Moreover according to the present invention, the arrangement of the circuit breaker allows no possibility of moistures entering into the protective cylinder 17 through the bottom plate 20 and of depositing carbonaceous substances on the inner surfaces of arc suppressing cylinder so that the danger of causing creeping discharge along the inner surface of the insulating cylinder. Thus the present invention is effective in promoting circuit interrupting ability of such circuit breakers and maintaining higher dielectric strength of insulating oil.

Having thus described our invention, what we claim as new and desire to secure by Letters Patent of the United States is:

1. In an electric circuit breaker, a protective insulator cylinder for containing insulating fluid, a fixed contact adjacent the bottom of said protective insulator cylinder, a movable contact reciprocably mounted adjacent the top of said protective insulator cylinder, means for reciprocating the movable contact into and out of engagement with the fixed contact, an arc suppressing cylinder of lesser diameter than the protective insulator cylinder mounted within the latter, forming with same part of an oil chamber and enclosing the fixed contact, a plurality of partitions having aligned apertures therein of slightly greater diameter than the movable contact through which the movable contact is adapted to pass with close clearance, and forming a series of oil filled arc suppressing chambers, an insulator cylinder of lesser diameter than the

protective insulator cylinder positioned within the latter in alignment with the arc suppressing cylinder forming with the protective insulator cylinder part of the oil chamber and having a bottom with an aperture therein and said bottom being spaced from the top of the arc suppressing cylinder to form an oil filled gap as part of the oil chamber, and means for reciprocating said movable contact through the aperture in the bottom of the insulator cylinder and the apertures in the partitions in the arc suppressing cylinder to and from engagement with the fixed contact.

2. An electric circuit breaker comprising an insulator bushing having a closed bottom forming an oil tank, an insulated support for the insulator bushing, a casing secured in the top of the insulator bushing, a protective insulator cylinder suspended from the casing and positioned within the insulator bushing and extending downwardly from the top of the latter into the oil tank, an arc suppressing cylinder of lesser diameter than the protective insulator cylinder positioned within the protective insulator cylinder and secured to the bottom of the latter and forming with same part of a main oil chamber, a fixed contact within the arc suppressing cylinder, means within the arc suppressing cylinder forming a series of separate oil filled arc suppressing chambers, an insulator cylinder of lesser diameter than the protective insulator cylinder suspended from said casing and positioned within the protective insulator cylinder in alignment with the arc suppressing cylinder forming with the protective insulator cylinder part of the main oil chamber having a bottom with an aperture therein and with said bottom forming with the arc suppressing cylinder an oil gap as part of the main oil chamber, a movable contact reciprocably mounted adjacent the top of said insulator cylinder, guide means at the top of the insulator cylinder for said movable contact and forming with the bottom of the insulator cylinder an arc extinguishing chamber, and means within said casing for reciprocating said movable contact through the arc suppressing chamber, the gap between the insulator cylinder and the arc suppressing cylinder, and the oil filled arc suppressing chambers within the arc suppressing cylinder into and out of engagement with the fixed contact whereby the insulating strength between the movable and fixed contacts is quickly restored upon the return stroke of the former by the arc being extinguished in the oil filled arc suppressing chambers within the arc suppressing cylinder, the gases emitted from the top of the arc suppressing cylinder being prevented from entering the arc suppressing chamber in the insulator cylinder as the movable contact is withdrawn through the aperture in the bottom of the latter by being dispersed in the oil gap between the insulator cylinder and the arc suppressing cylinder.

3. An electric circuit breaker comprising an insulator bushing having a closed bottom forming an oil tank, an insulated support for the insulator bushing, a casing secured in the top of the insulator bushing, a protective insulator cylinder suspended from the casing and positioned within the insulator bushing and extending downwardly from the top of the latter and terminating short of the bottom of the insulator bushing to form a chamber for the corroded oil below the bottom of the protective insulator cylinder, an arc suppressing cylinder of lesser diameter than the protective insulator cylinder positioned within the latter and secured to the bottom of the latter and forming with same part of a main oil chamber, means within the arc suppressing cylinder forming a series of separate oil filled arc suppressing chambers, an insulator cylinder of lesser diameter than the protective insulator cylinder suspended from said casing and positioned within the protective insulator cylinder in alignment with the arc suppressing cylinder forming with the protective insulator cylinder part of the main oil chamber and having a bottom with an aperture therein and with said bottom forming with the arc suppressing cylinder an oil gap as part of the main oil chamber, a movable contact reciprocably mounted adjacent the top of said insulator cylinder, guide means at the top of the insulator cylinder for said movable contact and forming with the bottom of the insulator cylinder an arc extinguishing chamber, and means within said casing for reciprocating said movable contact through the arc suppressing chamber, the aperture in the bottom of the insulator cylinder, the gap between the insulator cylinder and the arc suppressing cylinder, and the oil filled arc suppressing chamber within the arc suppressing cylinder into and out of engagement with the fixed contact whereby the insulating strength between the movable and fixed contacts is quickly restored upon the return stroke of the former by the arc being extinguished in the oil filled arc suppressing chambers within the arc suppressing cylinder, the gases emitted from the top of the arc suppressing cylinder being prevented from entering the arc suppressing chamber in the insulator cylinder as the movable contact is withdrawn through the aperture in the bottom of the latter by being dispersed in the oil gap between the insulator cylinder and the arc suppressing cylinder.
